CODED RAILWAY SIGNALING APPARATUS

Filed Dec. 3, 1943

Traffic governing code or steady energy applied here according as traffic is westbound or eastbound respectively: ## UNITED STATES PATENT OFFICE

2,357,234

CODED RAILWAY SIGNALING APPARATUS

Crawford E. Staples, Pittsburgh, Pa., assignor to
 The Union Switch & Signal Company, Swiss-
 vale, Pa., a corporation of Pennsylvania

Application December 3, 1943, Serial No. 512,723

8 Claims. (Cl. 246—63)

My invention relates to a railway signaling system for use in single track stretches through which are operated locomotives equipped with cab signal apparatus responsive to flow of coded alternating current in the track rails.

In application for Letters Patent of the United States Serial No. 412,279, filed September 25, 1941, by James J. Van Horn, now Patent No. 2,344,333, granted March 14, 1944, there is shown a signaling system for a single track railroad over which traffic may move in either direction. In the system shown in that application each track section in the track stretch, except for the portions of the track stretch adjacent a highway intersection or other location where short detector track circuits are required, is equipped with two track circuits, one for each direction of traffic. Means are provided to at times supply steady energy to either end of the track stretch, while the track circuits are arranged so that when the track stretch is vacant, this steady energy is cascaded from one section to another throughout the track stretch to energize traffic locking means at the other end of the track stretch and thus permit the direction of traffic in the track stretch to be reversed. In addition, there are means at each end of the track stretch effective after the stretch has been conditioned for either direction of traffic to supply coded energy to the section at the exit end of the track stretch, and the track circuit apparatus for each section is arranged so that this coded energy is cascaded from one section to another to the entrance end of the track stretch to control the signal at the entrance end of the stretch.

As shown in Fig. 4 of the application identified above, where a highway crossing is encountered, track sections employing steady energy track circuits are provided on either side of the intersection to control the highway crossing signals, while a line circuit is provided to carry around the approach sections at the highway crossing the steady and coded traffic governing energy employed in the rest of the track stretch.

In track stretches in which are operated locomotives equipped with cab signal apparatus responsive to flow of coded alternating current in the track rails it is necessary to arrange the trackway apparatus so that coded alternating current is supplied to the rails of each track section at the exit end of the section.

It is an object of this invention to provide means for use in a system of the type described for supplying coded alternating current to the

detector track sections equipped with track circuits employing steady energy.

A further object of the invention is to provide means of the type described and in which the coding relays which control the supply of coded alternating current to the detector track sections are energized from the line circuit over which coded traffic governing energy is transmitted around the detector sections.

Another object of the invention is to provide a system of the type described which is arranged so that one coding relay is connected across the line circuit when the stretch is conditioned for one direction of traffic and a second coding relay is connected across the line circuit when the stretch is conditioned for the other direction of traffic.

Another object of the invention is to provide a system of the type described which is arranged so that the coding relays associated with the crossing are normally disconnected from the line circuit and become connected thereto only after an approach section is occupied.

Another object of the invention is to provide a system of the type described which is arranged so that only one coding relay is connected to the line circuit at one time.

Other objects of the invention and features of novelty will be apparent from the following description taken in connection with the accompanying drawing, the single figure of which is a diagram illustrating a section of railway track equipped with apparatus embodying my invention.

I shall describe one form of coded railway signaling apparatus embodying my invention and shall then point out the novel features thereof in claims.

In practicing my invention I provide two coding relays at the highway intersection and employ one of these to supply coded alternating current to the track transformers at this location on movement of a train through the track stretch in one direction, and employ the other coding relay to supply coded alternating current to the track transformers at this location on movement of a train through the track stretch in the other direction. As long as the approach sections are vacant the circuit of the line wires extending around these sections is complete and coded or steady traffic governing energy may be transmitted over these line wires between the sections at either side of the approach sections, while the coding relays at the highway intersections are deenergized. When a train enters an

approach section, the circuit of the line wires is interrupted and one of the coding relays at the intersection is connected across the line wires so as to be operated by coded energy supplied to the line wires. When the train advances into the short section which includes the highway intersection, the coding relay is maintained energized from the line wires by a circuit established by one of the directional stick relays for the crossing signals, while the track relay for the intermediate section controls the supply of coded energy to the approach sections.

In the drawing there is shown a stretch of single track railroad over which traffic may move in either direction. The track stretch includes an intersection with a highway and this crossing is protected by suitable crossing signals XS, while the track stretch is divided into suitable track sections for controlling the crossing signals.

This invention is directed to means for supplying coded alternating current cab signal control energy to the short track section which includes the highway crossing, and to the approach sections at either side of this section. This invention is not concerned with the apparatus at other points in the track stretch or at the ends of the single track stretch except insofar as the equipment of this invention is intended to operate in conjunction with that apparatus, and the equipment at those locations may be constructed as shown in application Serial No. 412,279 of James J. Van Horn.

In order to simplify the disclosure and facilitate understanding of my invention, only the equipment for the approach sections, and for the adjacent ends of the adjoining sections has been shown in the drawing.

The rails 1 and 2 of the track stretch are divided by means of the usual insulated rail joints 3 into a number of track sections. Each of these sections is identified by the reference character T with a distinguishing prefix which also identifies the apparatus associated with that section.

To facilitate description of the equipment it will be assumed that the right-hand end of the stretch is east and that the left-hand end of the stretch is west so that train movements from left to right are eastbound and train movements from right to left are westbound.

The track section ICT is a relatively short section which includes the highway intersection. This section has at one side the eastbound approach section IBT, and at the other side the westbound approach section IDT, while means governed by traffic conditions in these sections are provided to control the relay XR which governs the crossing signals XS.

The short intermediate section ICT is provided for the purpose of insuring that on movement of a train through the track stretch in either direction, operation of the crossing signals will be continued until the train clears the intersection. If this method of operation of the crossing signals is not required, the section ICT may be omitted and the approach sections IBT and IDT may adjoin.

In the system shown in the drawing the track relays IBTR and IDTR cooperate with the track relay ICTR of the intermediate section ICT to control directional stick relays WSR and ESR, and the crossing signal control relay XR. However, the invention is not limited to the use of this form of crossing signal control apparatus

and an interlocking relay of well-known construction, or other appropriate apparatus, may be employed to control the crossing signals.

The approach sections IBT and IDT and the intermediate section ICT are provided with track circuits employing steady energy. Each of these track circuits includes a track battery connected across the section rails at one end of the track section and a track relay, designated TR with an appropriate prefix, connected across the section rails at the other end of the section.

Each track section in the track stretch is provided with a track transformer at each end of the track section. These track transformers are designated TT with an appropriate prefix to indicate the track section with which the transformer is associated, and also the end of the section at which it is located.

The track transformers located at the ends of sections IBT, ICT and IDT at which the track batteries are located have their primary windings connected in series with the track battery, while these primary windings are of relatively low resistance so as not to unduly restrict the supply of energy from the track batteries to the section rails.

The track transformers located at the track relay ends of sections have their primary windings connected in multiple with track relays, while resistors are included in series with the track transformer windings to restrict flow of track circuit energy in these windings. The track relay windings have such high impedance to alternating current that little energy from the track transformers flows in the relay windings.

As explained in the above-identified application of James J. Van Horn, each of the track sections IAT and IET is provided with two track circuits, one eastbound and one westbound. Each track circuit for each of these track sections includes a code following track relay at one end of the track section and a track battery at the other end of the section, and at each end of the section a coding relay CTM having contacts controlling connection of the associated track battery and track relay with the section rails.

Each of the code following track relays has associated therewith a front contact repeater relay FSA and a back contact repeater relay BSA. The relays FSA and BSA are of a type the contacts of which are slow to release, while each of these relays may have a snubbing resistor connected across the terminals of its winding to increase the release period of the relay. The relays FSA and BSA are proportioned so that their contacts will remain picked up throughout the longest code interval during which the supply of energy to the relay is interrupted.

The equipment at the highway intersection includes coding relays CTMW and CTME which operate as hereinafter explained to cause coded alternating current energy to be supplied to section ICT and to section IBT or section IDT.

The relays and other equipment except the track relays are supplied from suitable sources of direct current, such as storage batteries, not shown, located at appropriate points in the track stretch. The terminals of these sources are designated B and C in the drawing.

The alternating current supplied to the track transformers may be supplied from any suitable

source, not shown, the terminals of which are designated BX and CX in the drawing.

The construction and operation of the cab signal apparatus on the locomotives operated in the track stretch are not a part of this invention, and have not been shown in order to simplify the disclosure. The cab signal apparatus may be constructed as shown in Letters Patent of the United States No. 1,986,679, issued January 1, 1935, to L. V. Lewis.

The equipment is shown in the condition which it assumes when the track stretch is vacant and steady energy is supplied at the east end of the track stretch. As explained in the Van Horn application identified above, steady energy is supplied at the east end of the track stretch and is cascaded from one track section to another to the west end of the stretch to energize traffic locking means at that point.

The apparatus provided by this invention for the approach sections is arranged so that on the supply of steady energy to either end of the track stretch it will be transmitted over a line circuit around the approach sections to the portion of the track stretch at the other side of these sections.

As steady energy is supplied to the east end of section 7ET this energy feeds over back contacts of coding relay 7WETCM and picks up track relay 7EETR so that energy is supplied over front contacts 20 and 21 of track relay 7EETR to line wires 22 and 23, and over back contacts 25 and 26 of track relay 7WATR to coding relay 7EACTM. The circuit of line wire 23 includes front contact 27 of relay 7DTR, front contacts 28 and 29 of track relay 7CTR, and front contact 30 of track relay 7BTR.

Accordingly, when sections 7BT, 7CT and 7DT are vacant, the circuit of line wires 22 and 23 is complete and steady energy supplied to the line wires over front contacts of relay 7EETR is supplied over the line wires to relay 7EACTM and keeps its contacts 32 and 33 picked up so that steady energy is supplied from the track battery 7EATB and from the track transformer 7EATT and from the track transformer 7EATT to the rails of section 7AT.

The steady energy supplied from track battery 7EATB to the rails of section 7AT picks up the track relay, not shown, at the west end of this section and causes the supply of steady energy to be repeated throughout the other track sections to the west end of the single track stretch.

As the track stretch is vacant, energy is supplied to relay XR over the circuit which includes front contact 35 of relay 7CTR, front contact 36 of relay 7DTR and front contact 37 of relay 7BTR so contact 38 of relay XR is picked up and interrupts the circuit of crossing signals XS to prevent their operation at this time.

At this time the directional stick relays WSR and ESR are released, while the circuits of the coding relays CTMW and CTME are interrupted so that the contacts of these relays are released and do not establish the circuits of the associated track transformers.

If it is desired to condition the stretch to permit a westbound train to pass through the stretch, means not shown, at the right-hand or east end of the stretch are operated to permit clearing of the westbound signal at that point and to cut off the supply of steady energy to the east end of the stretch. When the supply of steady energy to the stretch is interrupted, the track relay for each section releases and cuts off

the supply of steady energy to the adjoining section so the supply of steady energy is cut off from the various sections in succession throughout the track stretch, while the contacts of the coding relays CTM are released and connect the associated track relays across the section rails.

At this time, therefore, relay 7EETR releases and cuts off the supply of steady energy to line wires 22 and 23 so relay 7EACTM releases and cuts off the supply of energy from battery 7EATB and transformer 7EATT to the rails of section 7AT and connects track relay 7WATR across the section rails.

When the supply of steady energy at the west end of the stretch is cut off, apparatus, not shown, at that location causes coded energy of suitable code frequency, such as 75 or 180 code frequency, to be supplied to the west end of the track stretch. The means for causing coded energy to be supplied to the west end of the stretch are not a part of this invention, and are shown and described in the application of J. J. Van Horn, identified above.

On the supply of coded energy to the west end of the track stretch, coded energy is cascaded through the successive track sections to section 7AT and coded energy is supplied over back contacts 32 and 33 of relay 7EACTM to relay 7WATR. Accordingly, relay 7WATR follows code and energy is supplied over its front contacts 25 and 26 to line wires 22 and 23, and is supplied over these line wires and over back contacts 20 and 21 of relay 7EETR to relay 7WETCM and operates it to supply coded energy from the track battery 7WETB and from the track transformer 7WETT to the rails of section 7ET, while the track circuit apparatus, not shown, at the east end of section 7ET causes coded energy to be repeated into the adjacent section.

In addition, as a result of code following operation of track relay 7WATR relays 7WAFSA and 7WABSA are picked up, and contact 40 of relay 7WABSA establishes the circuit controlled by contact 41 of track relay 7WATR for supplying energy to the primary winding of track transformer 7WBTT. Accordingly, coded alternating current is supplied to the rails of section 7BT at the exit end of the section, while the code frequency of this energy is determined by the rate of operation of track relay 7WATR.

When the westbound train enters section 7DT, track relay 7DTR releases and its contact 27 interrupts the supply of energy over the line wires 22 and 23 to coding relay 7WETCM and connects wire 23 to one terminal of the winding of coding relay CTMW, the other terminal of which is connected to wire 22. Accordingly, relay CTMW is connected across line wires 22 and 23 and is operated by coded energy supplied to these wires as a result of operation of relay 7WATR. When coding relay CTMW is operated by energy from line wires 22 and 23, coded energy is supplied over front contact 43 of relay 7CTR and contact 44 of relay CTMW to the primary winding of track transformer 7WDTT so that coded cab signal control energy is supplied to the rails of section 7DT at the exit end of the section, while the code frequency of this energy is governed by the rate of operation of relay CTMW which is determined by the rate of operation of relay 7WATR. The coded alternating current supplied to the rails of section 7DT operates the cab signal apparatus on the locomotive in this section to provide an appropriate signal indication.

On coding operation of relay CTMW, coded alternating current is supplied over its contact 48 to transformer IWCTT and thus to the rails of section 7CT to operate the cab signal equipment when the locomotive advances into section 7CT. 5

In addition, on release of relay IDTR, its contact 36 interrupts the circuit of relay XR so that contact 38 of relay XR releases and initiates operation of the crossing signals XS. On release 10 of relay IDTR, a pick-up circuit is established for relay WSR and includes front contact 45 of relay IBTR, back contact 46 of relay IDTR, and back contact 47 of relay ESR. Accordingly, relay WSR picks up at this time.

When the train enters section 7CT, track relay 1CTR releases and its contact 43 interrupts the circuit traced above for supplying coded alternating current to track transformer IWDTT, but does not affect the circuit including contact 48 of coding relay CTMW for supplying energy to the track transformer IWCTT so that cab signal control energy continues to be supplied to the rails of section 7CT at the exit end of the section. 20

On release of relay 1CTR, its contact 35 establishes a stick circuit for relay WSR. This circuit includes back contact 35 of relay 1CTR and front contact 50 of relay WSR and maintains relay WSR picked up when relays 1DTR and 1BTR are both released or are both picked up. 30

In addition, on release of relay 1CTR, its contacts 28 and 29 additionally interrupt the circuit of line wire 23, while wire 23 is connected over back contact 29 of relay 1CTR and front contact 51 of relay WSR to the right-hand terminal of the winding of relay CTMW so that relay CTMW continues to be operated by energy supplied over line wires 22 and 23 even though on release of track relay 1CTR, the circuit controlled by relay 1DTR for connecting relay CTMW across the line wires is interrupted. 40

When the train advances into section 7BT, track relay 1BTR releases and its contact 30 interrupts the circuit of line wire 23 and cuts off the supply of energy to coding relay CTMW and it ceases to operate so that energy is no longer supplied to the track transformers IWCTT or IWDTT. 45

When the train enters section 7BT, the cab signal apparatus on the locomotive is operated by coded alternating current supplied to the section rails through transformer IWBT at the west end of the section. 50

In addition, when relay 1BTR releases, its back contact 45 closes so that when the train vacates section 7DT, energy is supplied to relay WSR over the stick circuit which includes front contact 46 of relay 1DTR, back contact 45 of relay 1BTR and front contact 52 of relay WSR so relay WSR remains picked up after the train vacates section 7CT and track relay 1CTR picks up and its contact 35 interrupts the stick circuit which it controls for supplying energy to relay WSR. 55

When the train advances into section 7AT, track relay 1WATR remains released so coded energy is no longer supplied to the west end of line wires 22 and 23 and these wires are connected to coding relay 1EACTM. 60

In addition, when relay 1WATR ceases to follow code, relays 1WAFSA and 1WABSA release so that contact 40 of relay 1WABSA interrupts the circuit of transformer IWBT. 65

When the train vacates section 7CT, the track

relay 1CTR picks up and energy is supplied over front contact 35 of relay 1CTR, front contact 36 of relay 1DTR, and front contact 54 of relay WSR to relay XR so that its contact 38 picks up to discontinue operation of the crossing signals XS. 70

When the train vacates section 7BT, track relay 1BTR picks up and its contact 37 completes the circuit including front contact 35 of relay 1CTR and front contact 36 of relay 1DTR for supplying energy to relay XR so that relay XR remains picked up to prevent operation of the crossing signals. In addition, on picking up of relay 1BTR, its contact 45 interrupts the stick circuit which it controls for relay WSR and relay WSR releases. 75

When sections 7DT, 7CT and 7BT are vacated and the track relays for these sections are picked up, the circuit of the line wires 22 and 23 is complete, while coding relays CTME and CTMW are both disconnected from the line wires. 80

As explained in the above-identified application of J. J. Van Horn, steady energy may be supplied to the track stretch behind the train, and this steady energy will be cascaded throughout the track stretch as each track section is vacated. Accordingly, after the train vacates section 7ET, steady energy supplied at the east end of the section feeds over the back contacts of coding relay 1WEETM and picks up the contacts 20 and 21 of relay 1EETR so that the circuit of relay 1WEETM is interrupted and it is certain to remain released and maintain the circuit of track relay 1EETR. In addition, when relay 1EETR picks up, it contacts 21 and 20 connect line wires 23 and 22 to the terminals B and C of a source of current, and when relays 1BTR, 1CTR, and 1DTR are picked up to complete the circuit of line wires 22 and 23, energy is supplied over these line wires and over back contacts 25 and 26 of track relay 1WATR to coding relay 1EACTM so that its contacts pick up to cause steady energy to be supplied to the rails of section 7AT and to interrupt the circuit of relay 1WATR so that it remains released and maintains the circuit of relay 1EACTM. 90

As track relay 1EETR is steadily picked up, relay 1EEBSA remains released and prevents supply of energy to track transformer 1EDTT. 95

If the steady energy supplied at the east end of the track stretch is now cut off, and coded energy substituted therefor, this coded energy will be cascaded throughout the track stretch to condition the signal at the west end of the stretch to permit an eastbound train to enter the stretch. 100

On movement of an eastbound train through the track stretch, the equipment at the highway crossing operates in a similar manner to that described in detail above on movement of a westbound train through the track stretch. 105

When the stretch is conditioned for eastbound traffic, track relay 1EETR follows code and causes coded energy to be supplied to the line wires 22 and 23 at the right-hand or east end thereof, 110 while this energy is supplied over the line wires to relay 1EACTM and operates it to cause coded energy to be supplied to the rails of section 7AT. As a result of coding operation of relay 1EETR, the relays 1EEFSA and 1EEBSA are both picked up and contact 56 of relay 1EEBSA establishes the circuit including contact 57 of track relay 1EETR for supplying coded energy to track transformer 1EDTT. 115

When an eastbound train enters section 7BT, track relay 1BTR releases and its contact 30 in-

terrupts the circuit of line wire 23 and connects this line wire to the left-hand terminal of the winding of coding relay CTME, the other terminal of which is connected to wire 22. Accordingly, relay CTME is connected across wires 22 and 23 and is operated by coded energy supplied to these wires by track relay 7EETR. On coding operation of relay CTME, coded alternating current is supplied over front contact 43 of track relay 7CTR and contact 58 of relay CTME to the primary winding of track transformer 7EBTT so that coded alternating current energy is supplied to the rails of section 7BT to operate the cab signal apparatus on the locomotive present in section 7BT. In addition, on coding operation of relay CTME, coded alternating current is supplied over its contact 60 to transformer 7ECTT and thus to the rails of section 7CT to operate the cab signal equipment when the locomotive advances into section 7CT.

On release of relay 7BTR, its contact 37 interrupts the circuit of relay XR and its contact 38 releases and initiates operation of the crossing signals XS. Also on release of relay 7BTR, a pick-up circuit is established for relay ESR and is traced over front contact 46 of relay 7DTR, back contact 45 of relay 7BTR and back contact 52 of relay WSR, and relay ESR picks up at this time.

When the train advances into section 7CT, track relay 7CTR releases and its contact 43 cuts off supply of energy to transformer 7EBTT but does not affect the circuit controlled by contact 60 of relay CTME for supplying energy to transformer 7ECTT so that coded energy continues to be supplied to the rails of section 7CT to operate the cab signal apparatus while the locomotive is in this section.

In addition, on release of relay 7CTR, its back contact 25 establishes a stick circuit for relay ESR, this circuit including front contact 61 of relay ESR. Also on release of relay 7CTR, its contacts 28 and 29 additionally interrupt the circuit of line wires 22 and 23, while contact 28 connects wire 23 over front contact 63 of relay ESR to the left-hand terminal of the winding of relay CTME so that coding relay CTME continues to be operated by coded energy supplied to the line wires 22 and 23 by track relay 7EETR.

When the train advances into section 7DT, track relay 7DTR releases and its contact 27 cuts off supply of energy over line wires 22 and 23 to coding relay CTME and it ceases to operate. When the train is in section 7DT, the cab signal apparatus on the locomotive is operated by energy supplied from transformer 7EDTT.

When the train advances into section 7ET, track relay 7EETR remains released and connects line wires 22 and 23 to coding relay 7WECTM, while relays 7EEFSA and 7EEBSA release so that energy is no longer supplied to transformer 7EDTT.

On release of relay 7DTR, its back contact 46 is closed so that when the train vacates section 7BT and track relay 7BTR picks up, energy is supplied to relay ESR over the stick circuit which includes front contact 45 of relay 7BTR, back contact 46 of relay 7DTR, and front contact 47 of relay ESR. The energy supplied over this circuit keeps relay ESR picked up after the train vacates section 7CT and track relay 7CTR picks up.

When track relay 7CTR picks up, energy is supplied over front contact 35 of relay 7CTR, front contact 65 of relay ESR, and front contact 37 of

relay 7BTR to relay XR so that contact 38 of relay XR picks up to discontinue operation of the crossing signals XS.

When the train vacates section 7DT, track relay 7DTR picks up and its contact 46 interrupts the stick circuit for relay ESR so that it releases, but at this time relay XR is maintained energized by current supplied over front contact 36 of relay 7DTR.

When track relays 7BTR, 7CTR and 7DTR are picked up, the circuit of the line wires 22 and 23 is complete, and if steady energy is supplied to the west end of the track stretch so that track relay 7WATR is picked up to cause steady energy to be supplied to the line wires 22 and 23, this energy will be supplied over the line wires and over back contacts 20 and 21 of relay 7EETR to coding relay 7WECTM so that its contacts are picked up to cause steady energy to be supplied to the rails of section 7ET and to interrupt the circuit of track relay 7EETR so it remains released and maintains the circuit of relay 7WECTM.

It will be seen that the equipment is arranged so that, when the track stretch is vacant, the circuit of the line wires extending around the approach sections for the highway crossing is complete and coded or steady energy may be transmitted over these line wires to control traffic in the track stretch. When the stretch is vacant, the coding relays at the crossing are de-energized and cab signal control energy is not supplied to the approach sections. As long as one of the approach sections is occupied, the supply of energy over the line wires to the coding relays at the ends of the line circuit is prevented, while as soon as a train enters one of the approach sections, one or the other of the coding relays at the crossing is connected across the line wires so as to be operated to supply to the track sections at the exit ends thereof coded cab signal control energy of appropriate code frequency.

As the system is arranged so that only one coding relay is connected across the line wires at one time, the coding relays will not interfere with each other, and will operate to supply to the track rails coded energy of accurate code pattern.

While the invention has been illustrated and described in connection with a track stretch equipped with signaling apparatus of the type shown in application Serial No. 412,279 of James J. Van Horn, in which both steady and coded traffic governing energy is employed, the invention is not limited to use in such situations, but is equally applicable to track stretches equipped with signaling systems of other types in which coded energy is supplied at one end of the stretch at times and is supplied at the other end of the stretch at other times.

Although I have herein shown and described only one form of coded railway signaling apparatus embodying my invention, it is understood that various changes and modifications may be made therein within the scope of the appended claims without departing from the spirit and scope of my invention.

Having thus described my invention, what I claim is:

1. In cab signal energy supply means for use in a stretch of railroad track over which may move in either direction locomotives equipped with cab signal apparatus responsive to the presence of coded alternating current in the track rails, the rails of the track stretch being divided

into a plurality of successive track sections including a first, second, a third and a fourth section, said track stretch being provided with traffic governing apparatus of a type in which coded energy is supplied to one end of the track stretch at given times and is supplied to the other end of the stretch at other times, said second and third track sections each being provided with a track circuit including a track relay, a pair of line wires substantially coextensive with said second and third track sections and governed by the track relays of said track sections, the first and fourth track sections each being provided with track circuits employing coded energy and each having at the end of the section adjacent the end of the line wires coding means responsive to the supply of coded energy over the section rails from the opposite end of the section for supplying coded energy to the line wires and for also supplying coded alternating current to the rails of the adjoining track section, said first and fourth track sections each being provided with coding means operated by coded energy supplied over the line wires and controlling the supply of coded energy to the section rails at the end of the section adjacent the line wires, in combination, a first coding device controlling the supply of coded alternating current to the rails of the third track section at the end of said section adjacent the second track section, a second coding device controlling the supply of coded alternating current to the rails of said second track section at the end of said section adjacent the third track section, means effective on release of the track relay for the second section to prevent the supply of energy over the line wires to the coding means for the first section and to connect the second coding device across the line wires so that said second coding device is operated by coded energy supplied to said line wires at the end thereof adjacent the fourth track section, and means effective on release of the track relay for the third section to prevent the supply of energy over the line wires to the coding means for the fourth section and to connect the first coding device across the line wires so that said first coding device is operated by coded energy supplied to said line wires at the end thereof adjacent the first track section.

2. In cab signal energy supply means for use in a stretch of railroad track over which may move in either direction locomotives equipped with cab signal apparatus responsive to the presence of coded alternating current in the track rails, the rails of the track stretch being divided into the plurality of successive track sections including a first, a second, a third and a fourth section, said track stretch being provided with traffic governing apparatus of a type in which coded energy is supplied to one end of the track stretch at given times and is supplied to the other end of the stretch at other times, said second and third track sections each being provided with a track circuit including a track relay, a pair of line wires substantially coextensive with said second and third track sections and governed by the track relays of said track sections, the first and fourth track sections each being provided with track circuits employing coded energy and each having at the end of the section adjacent the end of the line wires coding means responsive to the supply of coded energy over the section rails from the opposite end of the section for supplying coded energy to the line wires

and for also supplying coded alternating current to the rails of the adjoining track section, said first and fourth track sections each being provided with coding means operated by coded energy supplied over the line wires and controlling the supply of coded energy to the section rails at the end of the section adjacent the line wires, in combination, a first coding device controlling the supply of coded alternating current to the rails of the third track section at the end of said section adjacent the second track section, a second coding device controlling the supply of coded alternating current to the rails of said second track section at the end of said section adjacent the third track section, means effective when the track relay for the second section is released and the track relay for the third section is picked up to permit energy supplied to the line wires at the end thereof adjacent the fourth track section to be supplied to said second coding device, and means effective when the track relay for the third section is released and the track relay for the second section is picked up to permit energy supplied to the line wires at the end thereof adjacent the first track section to be supplied to said first coding device.

3. In cab signal energy supply means for use in a stretch of railway track over which may move in either direction locomotives equipped with cab signal apparatus responsive to the presence of coded alternating current in the track rails, the rails of said track stretch being divided by insulated joints into an intermediate section having an approach section at each side thereof, said approach sections and said intermediate section each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the sides of said approach sections remote from said intermediate section, said traffic governing apparatus being effective when the stretch is conditioned for either direction of traffic to cause coded alternating current to be supplied to the rails of the approach section in advance of said intermediate section at the exit end of said approach section and to also cause coded energy to be supplied to the line wires at the end thereof in advance of said intermediate section, in combination, a coding device controlling the supply of coded alternating current to the rails of one approach section and to the rails of the intermediate section at the exit ends of said sections for one direction of traffic, another coding device controlling the supply of coded alternating current to the rails of the other approach section and to the rails of the intermediate section at the exit ends of said sections for the other direction of traffic, means controlled by the track relays of one of said approach sections and of said intermediate section for connecting one of said coding relays across said line wires, and means controlled by the track relays of the other of said approach sections and of said intermediate section for connecting the other of said coding relays across said line wires.

4. In cab signal energy supply means for use in a stretch of railway track over which may move in either direction locomotives equipped with cab signal apparatus responsive to the presence of coded alternating current in the track

rails, the rails of said track stretch being divided by insulated joints into an intermediate section having an approach section at each side thereof, said approach sections and said intermediate section each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the sides of said approach sections remote from said intermediate section, said traffic governing apparatus being effective when the stretch is conditioned for either direction of traffic to cause coded alternating current to be supplied to the rails of the approach section in advance of said intermediate section at the exit end of said approach section and to also cause coded energy to be supplied to the line wires at the end thereof in advance of said intermediate section, in combination, a coding device controlling the supply of coded alternating current to circuits over which energy is supplied to the rails of one approach section provided the track relay of the intermediate section is picked up and to the rails of the intermediate section at the exit ends of said sections for one direction of traffic, another coding device controlling the supply of coded alternating current to circuits over which energy is supplied to the rails of the other approach section provided the track relay of the intermediate section is picked up and to the rails of the intermediate section at the exit ends of said sections for the other direction of traffic, means controlled by the track relays of one of said approach sections and of said intermediate section for connecting one of said coding relays across said line wires, and means controlled by the track relays of the other of said approach sections and of said intermediate section for connecting the other of said coding relays across said line wires.

5. In a cab signal energy supply means for use in a stretch of railway track over which may move in either direction locomotives equipped with cab signal apparatus responsive to the presence of coded alternating current in the track rails, the rails of said track stretch being divided by insulated joints into an intermediate section having a first approach section at one side and a second approach section at the other side, said approach sections and said intermediate section each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of said approach sections remote from said intermediate section, said traffic governing apparatus being effective when the stretch is conditioned to permit traffic to move from the first to the second approach section to cause coded alternating current to be supplied to the rails of the second approach section at the exit end thereof and to cause coded energy to be supplied to said line wires at the end thereof remote from said first section, said traffic governing apparatus being effective when the stretch is conditioned to permit traffic to move from the second to the first approach section to cause coded alternating current to be supplied to the rails of the first ap-

proach section at the exit end thereof and to cause coded energy to be supplied to said line wires at the end thereof remote from said second approach section, in combination, a first coding device controlling the supply of coded alternating current to the rails of said first approach section at the end thereof adjacent the intermediate section and to the rails of the intermediate section at the end thereof adjacent the second approach section, a second coding device controlling the supply of coded alternating current to the rails of the second approach section at the end thereof adjacent the intermediate section and to the rails of the intermediate section at the end thereof adjacent the first approach section, means controlled by the track relays of the first approach and intermediate sections for connecting the first coding device across said line wires, and means controlled by the track relays of the second approach and intermediate sections for connecting the second coding device across said line wires.

6. In a cab signal energy supply means for use in a stretch of railway track over which may move in either direction locomotives equipped with cab signal apparatus responsive to the presence of coded alternating current in the track rails, the rails of said track stretch being divided by insulated joints into an intermediate section having a first approach section at one side and a second approach section at the other side, said approach sections and said intermediate section each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of said approach sections remote from said intermediate section, said traffic governing apparatus being effective when the stretch is conditioned to permit traffic to move from the first to the second approach section to cause coded alternating current to be supplied to the rails of the second approach section at the exit end thereof and to cause coded energy to be supplied to said line wires at the end thereof remote from said first section, said traffic governing apparatus being effective when the stretch is conditioned to permit traffic to move from the second to the first approach section to cause coded alternating current to be supplied to the rails of the first approach section at the exit end thereof and to cause coded energy to be supplied to said line wires at the end thereof remote from said second approach section, in combination, a first coding device controlling the supply of coded alternating current to circuits over which alternating current is supplied to the rails of said first approach section at the end thereof adjacent the intermediate section provided the track relay for the intermediate section is picked up and over which alternating current is supplied to the rails of the intermediate section at the end thereof adjacent the second section, a second coding device controlling the supply of coded alternating current to circuits over which alternating current is supplied to the rails of said second approach section at the end thereof adjacent the intermediate section provided the track relay for the intermediate section is picked up and over which alternating current is supplied to the rails of the intermediate section at the end thereof adjacent the first section, means con-

trolled by the track relays for the first approach and intermediate track sections for connecting the first coded device across said line wires, and means controlled by the track relays of the second approach and intermediate sections for connecting the second coding device across said line wires.

7. In cab signal energy supply means for use in a stretch of railway track over which may move in either direction locomotives equipped with cab signal apparatus responsive to the presence of coded alternating current in the track rails, the rails of said track stretch being divided by insulated joints into an intermediate section having a first approach section at one side and a second approach section at the other side, said approach sections and said intermediate section each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of said approach sections remote from said intermediate section, said traffic governing apparatus being effective when the stretch is conditioned to permit traffic to move from the first to the second approach section to cause coded alternating current to be supplied to the rails of the second approach section at the exit end thereof and to cause coded energy to be supplied to said line wires at the end thereof remote from said first section, said traffic governing apparatus being effective when the stretch is conditioned to permit traffic to move from the second to the first approach section to cause coded alternating current to be supplied to the rails of the first approach section at the exit end thereof and to cause coded energy to be supplied to said line wires at the end thereof remote from said second approach section, in combination, a first coding device controlling the supply of coded alternating current to the rails of said first approach section at the end thereof adjacent the intermediate section and to the rails of the intermediate section at the end thereof adjacent the second approach section, a second coding device controlling the supply of coded alternating current to the rails of the second approach section at the end thereof adjacent the intermediate section and to the rails of the intermediate section at the end thereof adjacent the first approach section, means controlled by the track relays of the first approach section and of the intermediate section for supplying from said line wires to the first coding device coded energy supplied to the line wires at the end thereof remote from the first approach section, and means controlled by the track relays of the second approach section and of the intermediate section for supplying from said line wires to the second coding device coded energy supplied to the line wires at the end thereof remote from said second approach section.

8. In cab signal energy supply means for use

in a stretch of railway track over which may move in either direction locomotives equipped with cab signal apparatus responsive to the presence of coded alternating current in the track rails, the rails of said track stretch being divided by insulated joints into an intermediate section having a first approach section at one side and a second approach section at the other side, said approach sections and said intermediate section each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of said approach sections remote from said intermediate section, said traffic governing apparatus being effective when the stretch is conditioned to permit traffic to move from the first to the second approach section to cause coded alternating current to be supplied to the rails of the second approach section at the exit end thereof and to cause coded energy to be supplied to said line wires at the end thereof remote from said first section, said traffic governing apparatus being effective when the stretch is conditioned to permit traffic to move from the second to the first approach section to cause coded alternating current to be supplied to the rails of the first approach section at the exit end thereof and to cause coded energy to be supplied to said line wires at the end thereof remote from said second approach section, in combination, a first coding device controlling the supply of coded alternating current to circuits over which alternating current is supplied to the rails of said first approach section at the end thereof adjacent the intermediate section provided the track relay for the intermediate section is picked up and over which alternating current is supplied to the rails of the intermediate section at the end thereof adjacent the second section, a second coding device controlling the supply of coded alternating current to circuits over which alternating current is supplied to the rails of said second approach section at the end thereof adjacent the intermediate section provided the track relay for the intermediate section is picked up and over which alternating current is supplied to the rails of the intermediate section at the end thereof adjacent the first section, means controlled by the track relays of the first approach section and of the intermediate section for supplying from said line wires to the first coding device coded energy supplied to the line wires at the end thereof remote from the first approach section, and means controlled by the track relays of the second approach section and of the intermediate section for supplying from said line wires to the second coding device coded energy supplied to the line wires at the end thereof remote from said second approach section.
